(57) **CLAIM**

The ornamental design for a bracelet helper tool hook, as shown and described.

DESCRIPTION

FIG. 1 is a front, top perspective view of a bracelet helper tool hook, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a front, top perspective view of the bracelet helper hook tool, wherein broken line showings of rubber covers are positioned on the tips of the clips; and,

FIG. 10 is an enlarged view of area 10 of FIG. 1.

The broken lines show portions of the bracelet helper tool hook that form no part of the claimed design.

The dashed lines in the figures illustrate portions of the bracelet helper tool hook that form no part of the claimed design.

The dot-dash broken lines of the bracelet helper tool hook in FIG. 1 illustrate a boundary and cut line of the enlarged view in FIG. 10 and form no part of the claimed design.
